UNITED STATES PATENT OFFICE.

ALBERT A. SPERRY, OF NEW BEDFORD, MASSACHUSETTS, ASSIGNOR TO THE PAIRPOINT MANUFACTURING COMPANY, OF SAME PLACE.

DESIGN FOR A SPOON, &c.

SPECIFICATION forming part of Design No. 20,776, dated May 26, 1891.

Application filed April 27, 1891. Serial No. 390,688. Term of patent 14 years.

To all whom it may concern:

Be it known that I, ALBERT A. SPERRY, of New Bedford, in the county of Bristol and State of Massachusetts, have invented and 5 produced a new and original Design for Spoon-Bowls, of which the following is a specification, reference being had to the accompanying drawings, forming part thereof.

Figure 1 is a plan, and Fig. 2 a lengthwise 10 section, of my newly-designed bowl with handle, these two views being deemed necessary to fully illustrate my design.

The feature of my design consists in a contraction of the side edges of the spoon at a 15 short distance from the junction of the bowl with the spoon-handle (the contractions being in line one with the other) to give the bowl a somewhat rounded or oval appearance at its inner end and an elongated taper 20 springing from the side contractions and extending to that end of the bowl which is opposite the handle, the elongated taper being longer than the distance from the junction of the bowl and handle to the line of the side 25 contractions.

A is the rounded or oval portion of the spoon adjacent to the junction *a* of the bowl and handle, and A' is the elongated tapered

portion of the bowl, this elongation springing from contractions *a'* of the side edges of 30 the bowl and being considerably longer than the distance from junction *a* to the line *a'* of the side contractions *a'*—that is, my new design may be considered, when viewed in outline, as being developed from an ellipse contiguous to the handle, with the major axis of this ellipse at right angles to the axis of the handle B, combined with half of an elongated ellipse whose major axis is at right angles to the major axis of the ellipse contiguous to 35 40 the handle; but of course I do not mean that my design is limited to its mathematical aspects above noted.

What I claim is—

The design for a spoon-bowl herein shown 45 and described, the same consisting of the rounded portion A contiguous to the handle and the elongated tapering portion A', formed by a contraction of the side edges of the bowl at *a' a'* and of a length greater than the distance of the line of contractions *a' a'* from the junction *a* of the bowl and spoon-handle B. 50

ALBERT A. SPERRY.
